UNITED STATES PATENT OFFICE

JOSEPH E. FALCK, OF PITTSBURGH, PENNSYLVANIA

DESIGN FOR A BURIAL CASKET

Application filed August 19, 1931. Serial No. 40,893. Term of patent 14 years.

To all whom it may concern:

Be it known that I, JOSEPH E. FALCK, a citizen of the United States, residing at Pittsburgh, in the county of Allegheny and State of Pennsylvania, have invented a new, original, and ornamental Design for a Burial Casket, of which the following is a specification, reference being had to the accompanying drawing, forming part thereof.

The figure is a perspective side view of a burial casket having plain ends and showing my new design.

I claim:

The ornamental design for a burial casket as shown and described.

JOSEPH E. FALCK.
